UNITED STATES PATENT OFFICE.

ARTHUR KÖHLER, OF CHEMNITZ, SAXONY, GERMANY.

BUTTON OR GLOVE-FASTENER.

SPECIFICATION forming part of Letters Patent No. 334,669, dated January 19, 1886.

Application filed October 20, 1885. Serial No. 180,386. (No model.)

To all whom it may concern:

Be it known that I, ARTHUR KÖHLER, a subject of the Duke of Saxe-Altenburg, residing at Chemnitz, in the Kingdom of Saxony, German Empire, have invented new and useful Improvements in Buttons, of which the following is a specification.

This invention relates to a button or fastener for gloves and similar articles. It consists in the elements of construction hereinafter more fully pointed out.

In the accompanying drawings, Figure 1 is a top view, partly in section, of my fastener. Fig. 2 is a sectional side view thereof. Fig. 3 is a top view of the same, showing it in position while being opened or closed. Figs. 4, 5, and 6 show a modified form of the button in side, top, and front view.

The ball k^3 is fastened to the part h^2 of the garment by means of the plates p' and p^2 , and a stud, s , covered by a bell, g , is secured to the part h' of the garment by means of the plates q' q^2 .

d' d^2 represent two shanks of a wire, which are bent so as to cross themselves, and to thus form two loops. One of these loops embraces the stud s , while the other loop embraces the shank of ball k^3 . The free ends of the wire shanks d' d^2 terminate in balls k' k^2 .

In opening or closing the garment, the balls k' k^2 are forced toward each other, to bend the wire shanks d' d^2 , and to permit the ball k^3 to pass out from between them. The device shown in Figs. 4, 5, and 6 is also opened by

pressing the balls k' k^2 one against the other, the only difference between this button and that which is above described consisting in the form of the plates bearing the stud s and the ball k^3 .

The plates q' and q^2 are provided with small hooks, which are thrust through the garment and then bent over.

I do not broadly claim to have invented a fastener consisting of two balls attached to a pair of spring-shanks, and adapted to interlock with a third ball attached to a neck, as such a construction is shown in Patent No. 281,376, granted to E. J. Kraetzer, July 17, 1883; but

I do claim—

1. The combination of the wire shanks d' d^2 , crossed to form two loops, and carrying balls k' k^2 , with the stud s and with the ball k^3 , all being so constructed that the stud s and the shank of ball k^3 are embraced by said loops, substantially as specified.

2. The combination of wire shanks d' d^2 , crossed to form two loops, with the balls k' k^2 k^3 and with the stud s , bell g , and plates p' q' , substantially as specified.

In testimony whereof I have signed my name to this specification in the presence of two subscribing witnesses.

ARTHUR KÖHLER.
